[57] CLAIM

The ornamental design for a paper hopper, as shown and described.

DESCRIPTION

FIG. 1 is an exploded perspective view of a paper hopper showing my new design;

FIG. 2 is a top plan view thereof;

FIG. 3 is a side elevational view thereof, the opposite side being a mirror image of the side shown;

FIG. 4 is a front elevational view thereof;

FIG. 5 is a bottom plan view thereof;

FIG. 6 is a rear elevational view thereof; and,

FIG. 7 is a cross sectional view taken on line 7—7 of FIG. 2.
